UNITED STATES PATENT OFFICE.

HENRY GEORGE ATWELL, OF FOX LAKE, ILLINOIS.

CLEVIS.

SPECIFICATION forming part of Letters Patent No. 660,068, dated October 16, 1900.

Application filed July 11, 1900. Serial No. 23,204. (No model.)

To all whom it may concern:

Be it known that I, HENRY GEORGE ATWELL, a citizen of the United States, residing at Fox Lake, in the county of Lake and State 5 of Illinois, have invented a new and useful Clevis, of which the following is a specification.

My invention relates to improvements in clevises; and the object of my improvement 10 is to furnish a clevis which may be attached to the evener or doubletree and singletree or whiffletree and connect the same without detachable pin or screw. I attain this object by the mechanism illustrated in the accompanying drawings, in which--

Figure 1 is a view of the entire and complete clevis when in use and attached to the evener and the whiffletree. Fig. 2 is a view of the clevis with the parts A and B swung 15 open, as they would be when the clevis is being attached to the evener or doubletree and the singletree or whiffletree, respectively, and also when disconnecting the same.

Throughout both views similar letters refer 20 to similar parts.

The clevis as proposed is composed of three metal sections—the part A, the tongue B, and the bar C, as shown in the drawings. Part e, as shown, is a metal pin securely set in part 25 A, as shown, by which the part A is held in contact with the bar C. The opening or slot in the bar C (marked d) is sufficiently large from right to left to permit the part A to be swung back on the bar C, as shown in Fig. 2, when attaching the clevis to the evener, and upon inserting that portion of the part

A marked x through the pin-hole in the evener and into the space marked b in the bar C, as shown at a and b in Fig. 1, the clevis is easily and securely fastened to the evener. The 40 draft against the arm x, as shown in Fig. 1, will cause the part A to remain securely inserted in the bar C at b, as shown. The tongue B, as shown, is a metal tongue inserted in the bar C at b and is held in position, as shown, by the metal pin f. Fig. 2 shows the tongue B raised to admit the ring of the whiffletree to the space marked o. Fig. 1 shows the tongue B as fallen down on the bar C, where it will remain of its own weight, 50 thus preventing the ring of the whiffletree from leaving the space o and becoming disconnected with the clevis. The spaces in bar C (marked b, d, and h, respectively, as shown in the drawings,) should be constructed 55 no larger than necessary to admit the part A and tongue B, as shown.

What I claim as my invention, and desire to secure and protect by Letters Patent of the United States, is—

A combination in a clevis of the part A, the bar C, and the tongue B, said parts being connected with each other, substantially as above set forth and described.

In testimony whereof I have signed my 65 name to this specification in the presence of two subscribing witnesses.

HENRY GEORGE ATWELL.
